UNITED STATES PATENT OFFICE.

GEORGE C. WRIGHT, OF NEW YORK, N. Y., ASSIGNOR TO E. S. HIGGINS & CO., OF SAME PLACE.

DESIGN FOR A CARPET-PATTERN.

Specification forming part of Design No. 6,011, dated July 23, 1872.

Specification describing a Design for Carpets, invented by GEORGE CURTIS WRIGHT, of New York, county of New York and State of New York.

The nature of my design is fully represented in the accompanying photographic illustration, to which reference is made.

A represents a panel surrounded with a Grecian border or frame-work; F, a figure resting on ground of panel A, and surmounted by figure G, circular in form. Small stems or vine-work radiate from frame B B toward figure F. H H are scrolls resting on frame B, forming part of said frame; E, a lozenged figure; C C, a panel corresponding in style to panel A; the whole resting on a ground composed of clover-leaves or shamrocks and vine of smaller leaves, forming a suitable ground-work for large centers. I prefer to make the center of panel A white; B, (or band,) brown and orange filled in with scarlet; G, blue, resting on scarlet ground; F, clover-leaf, brown

and yellow; small leaves, white, brown, and yellow; C C, scarlet ground, brown and yellow frame-work; the whole resting on a silver-drab ground.

I do not consider the colors selected to be an essential element in my design.

I am aware that carpet-patterns composed of panels and figures on a leaf or vine ground are not new, and I do not claim that feature.

The distinctive character of my design is found in the construction of bands surrounding panels, in combination with the scroll-work and figures inwrought into bands and body of design.

What I claim as my invention is—

A design for carpets in which the panels, bands, and ground-work are combined substantially in the manner above described.

GEO. C. WRIGHT.
